ELECTRODE HOLDER

Henry J. Wagner, Jackson, Mo.

Application June 30, 1938, Serial No. 216,802

3 Claims. (Cl. 219—8)

This invention relates to an electrode holder, the general object of the invention being to provide a holder that is attractive in appearance, convenient in its operation and one that will last for a long time and also one which will possess a grip on the electrode equally effective at any angle in which the electrode may be placed, thereby eliminating any loss of time in the operation.

10 Another object of the invention is to so make the jaws that they can be readily replaced with but the use of few tools.

Another object of the invention is to provide efficient and convenient means of attaching a 15 cable to the device without the use of solder and one which will provide full conductivity and eliminate the destructive effect of ordinary practices in making these connections.

This invention also consists in certain other 20 features of construction and in the combination and arrangement of the several parts to be hereinafter fully described, illustrated in the accompanying drawings and specifically pointed out in the appended claims.

25 In describing the invention in detail, reference will be had to the accompanying drawings wherein like reference characters denote like or corresponding parts throughout the several views, and in which:

30 Figure 1 is an elevational view of the device. Figure 2 is a longitudinal sectional view thereof.

Figure 3 is a view in perspective of several 35 of the parts of the invention disassembled.

Figure 4 is a view of the stationary jaw carrying member.

Figure 5 is a view of the two jaw members.

In these drawings the numeral 1 indicates a 40 cylindrical case of non-conducting material having one end partially closed but provided with an opening 2 for the passage of the conductor and its other end open with a ring 3, preferably of seamless steel tubing therein. The main or stationary holder bar is shown at 4 and is of 45 channel-shape construction for the major portion of its length but has a tubular part 5 at its rear end and at its front end the flanges are bent to provide the dovetail formation 6. Intermediate its ends this bar 4 is upwardly offset as shown at 7 and the ring 3 passes around this part 7 and is fastened thereto by a rivet 8 or the like. The part of the bar forwardly of the portion 7 extends from the open end of the case. The formation 6 slidably receives the 50 dovetail rib 9 of the jaw 10 the gripping face of

which is of slightly V-shape in cross section with the walls corrugated as shown at 11.

The movable holder bar is shown at 13 and this bar is also of channel shape for the major portion of its length but has the flanges at its outer end bent inwardly to provide the dovetail formation 14 for receiving the dovetail rib 15 of the plain jaw 16, the gripping face of this jaw 16 being slightly rounded in cross section to fit partly in the V-shaped face of the jaw 10. 10 This member 13 is also formed with an offset intermediate part 17 which passes through the ring 3 and a pivot pin 18 passes through the ring and this part 17 of the member 13 to permit rocking movement of the member 13. The 15 rear end of the member 13 is reduced and slightly curved as at 20 and this end fits in a groove 21 formed in an operating lever 22, the inner end of which is enlarged and of arcuate shape as shown and this end has a notch 23 therein 20 which engages the front wall of an opening 24 formed in an intermediate part of the casing 1. Thus the operating lever is rockingly supported by the case for moving the member 13 on its pivot 18. A substantially U-shaped spring 25 25 has one limb resting in the member 4 and its other end engaging the rear part of the member 13 and tends to hold the outer ends carrying the jaws 10 and 16 in closed position. The rear end 20 is pivoted in the groove 21 of the lever 22 by a pin 26 30 and one or more screws 27 fasten the member 4 in the case. The tubular part 5 of the member 4 is provided with a socket which has an enlarged front end which is screw-threaded and a gradually tapering rear end which is corrugated as shown in Figure 2. A screw 28 having 35 a large head part and a tapering shank corrugated as shown in Figure 2 is adapted to fit in the socket, the screw having a pointed end. Thus by placing the stripped end of the cable 40 in the socket and then inserting the screw the pointed end will spread the wires of the cable apart and the corrugated socket and corrugated shank will firmly bind the wires in the member 5, it of course being understood that the cable 45 is passed through the opening 2. The sleeve or part 5 and the screw both being corrugated will firmly hold the cable in position, thus making it difficult for the cable to pull from the device as frequently occurs when the device is being 50 dragged around over the floor and elsewhere.

A channel-shaped member 30 of non-conducting material fits over the outer end of each of the members 4 and 13 and is fastened thereto by the screws 31 and a protective shield of metal 55

32 covers each member 30 and these members 32 have large holes 33 therein so that these members 32 will not contact the screws 31.

I prefer to make the bars or members 4 and 13 of steel electro-plated with copper and to make the jaws 10 and 16 of copper.

The device is positive in action and holds the electrode with a firm grip and the insulation for the gripping jaws prevents accidental and destructive flashes and protects them from the heat of the arc, and this insulation is protected by a plate or armor which is in turn protected from current carrying parts of the holder. The spring is entirely enclosed and protected from any harm 15 and provides a powerful grip of the jaws on the electrode, whether these be small or large. The replacement of the gripping jaws can be accomplished practically without the use of tools as they are held in place by the dovetail parts and the 20 cable holding means maintains the flexibility of the cable and no heat is built up in the cable or in the connection. Every strand of the cable is brought into contact and so gripped as to provide the utmost of security and in a manner that prevents individual strands from injury and breakage.

It is thought from the foregoing description that the advantages and novel features of the invention will be readily apparent.

30 It is to be understood that changes may be made in the construction and in the combination and arrangement of the several parts provided that such changes fall within the scope of the appended claims.

35 Having described the invention, what is claimed as new is:

1. An electrode holder of the class described comprising an elongated case of insulating material having an opening in its rear end and its 40 other end being open, a ring fitting in said other end, a stationary bar of substantially channel-shape in cross section having a part fitting in the case and attached thereto and another part projecting from the open end of the case, said projecting part forming a dovetail-shaped groove, a jaw having a dovetail rib fitting in the groove, a second bar pivoted to the ring and having a part projecting from the case, said part being formed with a dovetail-shaped groove, a second jaw having a dovetail rib fitting in the last-mentioned 50 groove, a substantially V-shaped spring in the case engaging the two bars and tending to hold the jaws in closed position, a lever having a part

passing through an opening in the case and connected to the inner end of the pivoted bar, a sleeve at the inner end of the stationary bar having a socket therein the forward portion of which is threaded and the other portion is tapered and corrugated, a screw having a threaded head portion fitting in the threaded part of the socket and a tapered shank having corrugations for holding the end of the cable between itself and the corrugated part of the socket, members of non-conducting material covering the projecting ends of the bars and metal shields covering the members of non-conducting material.

2. An electrode holder of the class described comprising an elongated case of insulating material having one end open, a ring fitting in said open end, a stationary bar of substantially channel-shape in cross section having an intermediate part passing through and fastened to the ring with an end portion of the bar projecting from the open end of the case, a jaw having a rib thereon fitting in the projecting part, a second bar having an intermediate part passing through the ring and pivoted thereto with an end portion of the second bar projecting from the case, said second bar also being of channel-shape in cross section, a second jaw having a rib thereon fitting in the projecting end of the second bar, a substantially V-shaped spring in the case and engaging the two bars and tensioned to hold the jaws in closed position, said case having an opening at an intermediate part thereof, a lever having a part passing through said opening and connected to the inner end of the pivoted bar and means for connecting a cable to the inner end of the first bar.

3. An electrode holder of the class described comprising an elongated case of insulating material, an elongated stationary bar having a portion fastened in the case and another portion projecting therefrom, a jaw carried by the projecting portion, a second bar having an intermediate part pivoted in the case with a portion projecting from the case, a jaw carried by said projecting portion, a spring engaging that portion of the last-mentioned bar which is located in the case for holding the jaws in engagement, said case having an opening at an intermediate portion thereof, a lever having an enlarged end provided with a notch, said notch receiving a portion of the wall of the opening and means for pivoting the inner end of the pivoted bar with the enlarged part of the lever.

HENRY J. WAGNER.
